DRIVING AND STOPPING MECHANISM FOR
SEWING MACHINESClyde L. Knott, Beverly, Mass., assignor to United
Shoe Machinery Corporation, Flemington, N. J.,
a corporation of New Jersey

Application October 15, 1943, Serial No. 506,319

15 Claims. (Cl. 192—146)

1

The present invention relates to driving and stopping mechanisms and is hereinafter illustrated as embodied in a heavily constructed shoe sewing machine of the type disclosed in an application for United States Letters Patent Serial No. 194,594, filed in the name of the present inventor on March 8, 1938, now Patent No. 2,332,649, granted October 26, 1943, in which the main shaft is driven positively at a lower speed while the machine is being brought to rest than during sewing, the lower speed of the main shaft being such that the reduction in speed will enable the shaft readily to be stopped at a predetermined position with the stitch forming devices free of the work operated upon.

In certain types of driving and stopping mechanisms, particularly for shoe sewing machines, it is convenient to provide a drive shaft having a clutch thereon actuatable by lengthwise movement of the drive shaft and, as a means for connecting the drive shaft with other rotating parts, there is provided a helical or spiral gear on the drive shaft meshing with a corresponding gear on a second adjacent shaft, the driving reaction of the inclined teeth on one gear tending, under some circumstances, to thrust the teeth on the other gear axially and to move the drive shaft lengthwise in a direction which will prevent disengagement of the clutch. Also, the mechanism for driving the sewing shaft of such a machine at lower speed before bringing it to rest, includes a radially cut timing cam connected to a low speed braking clutch member and a follower engaging the cam at one side of the shaft on which it is slidably mounted to throw the lower speed driving mechanism into operation. The cam follower is coupled automatically at the end of an operation to a yielding slide which acts to resist movement of the follower, thereby causing the low speed braking clutch member and cam to be moved bodily along the shaft toward its cooperating clutch member and the speed of the shaft to be reduced and then the shaft to be driven through a predetermined portion of a rotation. After being driven through a predetermined portion of the rotation, the cam moves the clutch member out of engagement with its cooperating clutch member and the shaft is brought to rest. The speed of rotation at the lower speed thereafter is insufficient to cause the shaft to be rotated beyond a predetermined stopping position so that the machine may be stopped accurately in proper stopping position and with the smallest possible delay.

Due to the arrangement of the radially cut

2

timing cam and the follower engaging the cam at one side of the shaft, the sliding movement of the cam on the shaft may be impeded to some extent by frictional resistance produced as a result of unsymmetrical application of the pressure between the cam and the follower. Also after the parts have become worn, the resulting looseness may affect adversely an even application of pressure throughout the area of the clutching surfaces between the low speed braking clutch members. Where uneven braking and clutching pressures exist between clutching surfaces, these surfaces when in use show indications of excessive wear and the driving power of the clutch is substantially impaired within a short time after the clutch is adjusted to take up looseness from wear.

It is a general object of the present invention to provide a driving and stopping mechanism for a heavily constructed shoe sewing machine in which the difficulties above referred to are avoided and the operation and construction of which are substantially improved. A further object of the invention is to prevent the reaction of a helical gear drive connection between adjacent rotating shafts, one of which is movable lengthwise and carries a clutch member thereon, from affecting the disengagement of the clutch adversely and to provide a controlling arrangement for such a drive connection in which the driving reaction will improve the ease of control and the effectiveness of the clutch.

Other objects are to simplify and improve the construction and mode of operation of a low speed braking clutch in a driving and stopping mechanism to secure the greatest possible efficiency with the clutching surfaces employed and to reduce the likelihood, even after excessive wear, of uneven pressures between the clutching surfaces or of improper movements of the clutch members toward and from each other.

In the attainment of these and other objects, one feature of the invention is embodied in a driving and stopping mechanism having a drive shaft, a clutch actuatable by movement lengthwise of the shaft, manually operable means for controlling the clutch pressure, and a helical gear transmission connected to the shaft and formed with teeth inclined to the axis of the shaft in a direction tending to throw the clutch out of operation while a load is being imposed on the transmission so that an accurate and smoothly responsive manual control of the clutch pressure may be obtained. This construction and arrangement enables the rotation of the shaft to

be controlled effectively at all times and the clutch to be engaged and disengaged readily so long as the parts are rotating idly. As soon as a load is applied to the helical gear transmission, there is a tendency to separate the members of the clutch or to cause the clutch to slip, depending upon the force applied to move the shaft lengthwise. Also, there is no reaction of the helical gear transmission to prevent disengagement of the clutch members either when it is desired to bring the machine to rest or, in starting the machine, to cause a sudden uneven engagement of the clutch. In the particular construction hereinafter described, one clutch member is fixed on the drive shaft and consists of a plate disposed between a pair of separate clutch members. The helical gear on the drive shaft is slideable lengthwise on but is mounted to rotate with the shaft, an end thrust bearing for said helical gear being provided to prevent the reaction of the inclined gear teeth from moving the clutch plate beyond a neutral position between said clutch members and thereby to hold it out of driving relation with both clutch members.

Another feature of the present invention relates to the use of thrust means engaging a radial surface on a low speed braking clutch member having a radially cut cam for throwing the clutch member into and out of operation, said thrust means being located at the side of the main shaft supporting the clutch member opposite from a follower engaging the radially cut cam to equalize the pressure throughout the area of the clutching surfaces between the clutch member and its driver. Thus, the highest possible driving force is obtainable with minimum areas of clutching surfaces, the surfaces being pressed together uniformly throughout their extent and not with greater pressure along one portion than another. In this way, excessive wear is avoided on the clutching surfaces when under heavy pressure, and when the surfaces are under relatively light pressure, they are effective to produce a maximum possible rotational force in the main shaft on which the clutch members are mounted. In accordance with this feature, the follower engaging the cam is coupled to a yielding slide to cause the clutch member to engage its driver, and the thrust means is yieldingly connected to the slide so that inequalities in the clutching pressure at opposite sides of the shaft will be taken up and concentrated application of heavy pressures when operating at high speeds will be prevented.

These and other features consisting of certain constructions, arrangements and combinations of parts will be apparent to those skilled in the art from the following description taken in connection with the accompanying drawings, in which

Fig. 1 is a view in side elevation, partly broken away of a high speed heavily constructed shoe sewing machine having a driving and stopping mechanism embodying the features of the present invention;

Fig. 2 is a right side view, partly in section and partly broken away, of the portion of the machine including the driving and stopping mechanism taken in a plane passing through the main sewing shaft for the machine and through the drive shaft;

Fig. 3 is a detail view illustrating the same parts of the machine taken in vertical section at right angles to the section of Fig. 2;

Fig. 4 is a plan view of a portion of the low speed driving mechanism on the main shaft of the machine;

Fig. 5 is a view in side elevation and partly in section of the drive shaft, illustrating the positions of the parts while the machine is operating at high speed; and

Fig. 6 is a similar view illustrating the positions of the parts while the machine is operating at intermediate speed.

The machine herein illustrated is the same except as hereinafter described as that disclosed in the patent application above referred to and is a heavily constructed shoe sewing machine having a sewing head 2 which is mounted upon the upper end of a frame 4 of generally rectangular vertical section connected to a base 6 of similar shape. The machine is driven by an electric motor 8 carried at the rear of the base 6 through connections including a belt 10 passing about a pulley 12 fast to an intermediate drive shaft 14 for the main driving means of the machine. The main driving means is connected by a pair of pulleys 16 and 18 on the shaft 14 about which are carried belts 20 and 22, respectively, extending to pulleys 24 and 26 fast to a main sewing and operating shaft 28 (see Figs. 1, 2, 3 and 4). The devices operated by the main shaft 28 comprise the sewing instrumentalities of a heavily constructed McKay type machine including a straight hook needle 30 and a looper for threading the needle contained within a rotatable shoe supporting horn 32 mounted on the main frame 4 of the machine. The main driving means acts, upon depression of a control treadle 34 mounted in the base 6, to connect the continuously rotating motor with the main shaft 28 and, upon release of the treadle, a low speed driving and braking mechanism is thrown into operation, first, to act as a brake in reducing the speed of the sewing shaft 28 and, then, to drive the sewing shaft until a predetermined position of the shaft is reached with the needle disengaged from the work.

The main driving means comprises clutches formed by the pulleys 16 and 18 which are rotatable on the shaft 14 and a central clutch plate 36 secured to the shaft 14 and disposed between the pulleys 16 and 18. The shaft 14 is so mounted as to be capable of slight longitudinal movement, and the clutch plate 36 is provided at opposite sides with facings 38 the surfaces of which cooperate with flanges formed on the pulleys 16 and 18 so that, when the shaft 14 slides longitudinally, the plate 36 will be forced into driving relation with one or the other of the pulleys. The pulleys 16 and 18, 24 and 26 have different diameters so that the belts 20 and 22 will cause the operating shaft 28 to rotate at different speeds when one clutch or the other is closed.

The low speed driving and braking mechanism is mounted on the main sewing and operating shaft 28 and is similar to that disclosed in United States Letters Patent No. 1,099,328, granted June 9, 1914, upon an application of Laurence E. Topham and No. 1,298,758, granted April 1, 1919, upon an application of William C. Meyer, which have a low speed worm wheel similar to that indicated at 40 rotatable on the operating shaft. The worm wheel 40 is driven through a worm 42 secured to a cross shaft 44 provided at its outer end with a pulley 46. The worm wheel has an inner conical clutching surface arranged to cooperate with a correspondingly shaped surface on a movable clutch member 48 rotatable with but slideable along the operating shaft 28. The hub of the movable clutch member is provided with a radially cut timing cam slot 50 in which a cam

follower 52 rides so that the cam follower is vibrated continuously along the operating shaft while the machine is running. The cam follower 52 is mounted on one arm of a vibrating bell crank 54 fulcrumed on a stud 56 secured in the head 2 of the machine, and another arm of the bell crank has an elongated recess or slot into which the upper end of a vertical lock bolt or pin 58 may enter to couple the bell crank to a horizontally movable carrier or slide 60 for the lock bolt 58, the lock bolt being spring pressed upwardly into engagement with the recess in the vibrating bell crank 54. The carrier 60 is acted upon by a spring 62 coiled about one end of a threaded rod 64 projecting from the carrier 60. The spring 62 extends beyond the end of the rod 64 and surrounds the end of a bolt 66 spaced from the end of the rod 64 and secured in the head 2 of the machine, thus urging the carrier 60 yielding toward the right of Fig. 3. The rod 64 carries check nuts 68 for compressing the spring 62 and for limiting the expansion of the spring when the check nuts come into engagement with the side portion of the head 2 in which the carrier slides. When the lock bolt 58 enters the recess in the bell crank 54, the bell crank is restrained from vibration and the cam slot 50 causes the follower 52 to press the movable clutch member 48 into engagement with the worm wheel 40 for a predetermined part of a rotation. When the speed of the main shaft 28 is substantially reduced by the braking effort of the clutch, the clutch member 48 is disengaged from the worm wheel 40 and the main shaft brought to rest, the rotation of the worm wheel being at such a low speed that the momentum of the main shaft is quickly overcome by friction.

For driving the pulley 46 of the low speed driving and braking mechanism, there is a belt 70 surrounding the pulley 46 and a continuously rotating pulley 72 secured to the outer end of a shaft 74 supported in suitable bearings, the axis of which shaft passes at right angles to the intermediate drive shaft 14. The shaft 74 is driven by means of helical gears 76 and 78 made fast respectively to the drive shaft 14 and the shaft 74.

When the treadle 34 is first depressed with the machine at rest, the lock bolt 58 is withdrawn from engagement with the bell crank 54, thus rendering the low speed driving and braking mechanism inoperative and, by the same movement of the treadle, the clutch plate 36 is pressed into frictional engagement with the pulley 16, as illustrated in Fig. 6, to drive the main shaft. When the treadle is depressed further, the clutch plate 36 is disengaged from the pulley 16 and forced positively against the driving pulley 18, as indicated in Fig. 5, against the force of a spring 77 by power actuated mechanism 79 driven by the helical gear 78, described more fully in the application referred to, so that the main shaft 28 will be rotated at a higher speed. While the machine is at rest, the spring 77 retains the clutch plate 36 out of engagement with the pulley 18.

The treadle connections for moving the drive shaft 14 longitudinally act directly and include a vertical link 80 (see Fig. 1), a three-armed lever 82, and a horizontal rod 84 connecting the lever with a forked shifting lever 86 having pins engaging the collar 88 on the drive shaft 14. These connections are effective to shift the shaft 14 longitudinally and to bring the clutch plate against the pulley 16 with the desired pressure, as shown in Fig. 6, but, when a sudden load is imposed on the helical transmission gears 76, 78, unless the inclination of the gear teeth is in the

proper direction with respect to the axis of the shaft, there is a tendency to move the shaft and the clutch plate 36 forcibly with a substantial impact against the pulley 16, thereby interfering with the proper control of the machine and preventing the clutch from being disengaged from the pulley 16 when it is desired to reduce the speed or disengage the clutch plate 36 wholly from the pulley 16, as in Fig. 2.

According to a feature of the present invention, the angular relation of the inclined teeth on the gears 76 and 78 to the axis of the drive shaft is so arranged that the only reaction on the shaft when a sudden load is imposed on the gears, is in a direction to move the clutch plate away from the clutching surface of the pulley 16 and throw the low speed clutch out of operation. Thus, there is no opportunity for the low speed clutch 36, 16 to act erratically during engagement, to grab or to remain in engagement when it is desired to disengage the plate from the pulley 16.

To prevent the reaction of the helical gears 76 and 78 from forcing the clutch plate 36, after being disengaged from the clutching surface of the pulley 16, against the clutching surface of the pulley 18, the endwise movement of the gear 76 is limited by an end thrust bearing 90 on the frame 4, as shown in Fig. 5. In order that the drive shaft 14 and the clutch plate 36 may be moved to drive the pulley 18, the helical gear 76 is slidably mounted on the shaft 14 and is provided with a key 92 loosely fitting a keyway in the shaft 14, and the shaft is formed with a shoulder 94 against which the gear 76 presses to disengage the clutch from the pulley 16 and to maintain the plate in a neutral position between the clutch pulleys 16 and 18 out of driving engagement with either one. A suitable clearance space 96 is provided between the gear and the bearing portion of the frame 4 in which the shaft 14 rotates at the side of the gear 76 opposite the thrust bearing 90. Thus, the clutch plate 36 and its supporting drive shaft 14 may be shifted to engage either of the clutch members consisting of the pulleys 16 and 18 and may be disengaged without any substantial resistance being offered to their movements by the transmission comprising the helical gears 76 and 78.

The location of the cam follower 52 at one side 50 of the main shaft 28 causes one portion of the movable clutch member 48 to be pressed with greater force than another against the worm wheel 40 particularly when the parts become worn and excessive looseness exists between the bearing 55 surfaces of the clutch member 48 on the main shaft 28. Also, the application of pressure by the follower 52 on the cam 50 at one side of the center of rotation produces a tilting movement of the cam on the shaft 28 about an axis transverse to the shaft 28 in such a way as to increase the frictional resistance against sliding movement of the clutch member 48 on the shaft toward and from the worm wheel 40.

To equalize the forces acting on the movable clutch member 48 at both sides of its center of rotation with the shaft 28, according to a further feature of the invention, the lock bolt carrier 60 has yieldingly connected with it a lever 98 for a thrust roll 100 rotatably mounted in one arm of the lever to press against a radial surface 102 on the clutch member 48 at the opposite side of the shaft 28 from the cam follower 52. When the lock bolt 58 couples the lock bolt carrier to the bell crank 54, the carrier 60 is moved slightly as the clutch member 48 is pressed against the worm

wheel, and this slight movement is sufficient to transmit a corresponding movement to the lever 98 which is fulcrumed on a pin 104 secured in the sewing head 2 of the machine. For transmitting movement to the lever 98, an arm of the lever slidably receives a pin 106 around which is coiled a compression spring 108 acting at one end against the arm of the lever 98 and at the other end against a shoulder on the carrier 60. The pin 106 is fixed at one end in the carrier 60 and has at the other end a pair of check nuts 110 for limiting the movement of the lever 98 under the force of the spring 108. During normal sewing operations when the lock bolt 58 is disengaged from the bell crank 54, the check nuts hold the thrust lever 98 in a position with the roll 100 disengaged from the surface 102. The arrangement is such that the lever 98 will move the roll 100 against the surface 102 as soon as the roll 52 on the bell crank begins to press the clutch member towards the worm wheel 40. Since the roll 100 engages the surface 102 at a greater distance from the center of the shaft 28 than the point of contact of the cam roll 52 with the cam slot 50, the spring 108 is so constructed that its pressure together with the pressure of the spring 62 will be inversely proportional to the ratio of the distances between the cam follower 52 and the center of the shaft to the roll 100 and the center of the shaft. In this way, the forces applied by the follower 52 and the roll 100 will exactly balance each other about the shaft 28 as a center, and the pressure of the clutch member 48 on the worm wheel 40 at either side of the shaft will be equalized.

To hold the clutch member 48 out of engagement with the worm wheel 40, the clutch member has connected to it a pair of tension springs 112 at opposite sides of the shaft 28 stretched between the clutch member and a pair of pins 114 fastened at diametrically opposite points on the outer surface of the shaft.

For convenience in construction and operation, the lock bolt is actuated through connections acting to withdraw the lock bolt from the bell crank 54 immediately during the first part of the downward depression of the foot treadle 34. These connections include a rod 116 pivotally connected between the lower end of the lock bolt and a lever 118 fulcrumed on a stud 120, a cam lever 122 fulcrumed on a screw 124 having a cam surface engaged by a roll 126 on the lever 118 and a rod 128 pivotally connected between the cam lever and an arm of the treadle actuated lever 82.

The nature and scope of the invention having been indicated and a specific embodiment thereof having been described, what is claimed is:

1. A driving and stopping mechanism having, in combination, a drive shaft, a clutch actuatable by movement lengthwise of the shaft, manually operable means for controlling the clutch pressure, and a helical gear transmission connected to the shaft and formed with teeth inclined to the axis of the shaft in a direction to throw the clutch out of operation when the clutch pressure is partially released with a load imposed on the transmission.

2. A driving and stopping mechanism having, in combination, a shouldered drive shaft, a clutch actuatable by lengthwise movement of the shaft, manually operable means for controlling the lengthwise movement of the shaft, and a transmission comprising a helical gear slidable on but mounted to rotate with the shaft, the teeth of said gear being cut at an inclination to the axis of the shaft to cause the clutch to be thrown out

of operation when the shaft is moved to release the clutch pressure with a load imposed on the transmission.

3. A driving and stopping mechanism having, in combination, a shouldered drive shaft, a clutch actuatable by lengthwise movement of the shaft, manually operable means for controlling the lengthwise position of the shaft, a transmission comprising a helical gear slidable on but mounted to rotate with the shaft, the teeth of said gear being cut at an inclination to the axis of the shaft to cause the clutch to be thrown out of operation when the shaft is moved to release the clutch pressure with a load imposed on the transmission, and a thrust bearing for said helical gear for preventing lengthwise movement of the shaft after the clutch is rendered inoperative.

4. A driving and stopping mechanism having, in combination, a drive shaft, a pair of clutch members rotatable on the shaft, a central clutch plate between the clutch members, means for shifting the shaft lengthwise to press the clutch plate against either of said members, a transmission comprising a helical gear slidable on but mounted to rotate with the shaft, the teeth on said gear being cut at an inclination to the axis of the shaft to cause the shaft to move the clutch plate under reaction of load on the transmission away from one of said pair of members when the pressure of the clutch plate on said one clutch member is relieved, and an end thrust bearing for said helical gear for preventing the shaft from being moved by said gear beyond a neutral position between said clutch members.

5. A driving and stopping mechanism having, in combination, a drive shaft, a pair of clutch members rotatable on the shaft, a central clutch plate between the clutch members, means for shifting the shaft lengthwise to press the clutch plate against either of said members, a transmission comprising a helical gear slidable on but mounted to rotate with the shaft, the teeth on said gear being cut at an inclination to the axis of the shaft to cause the shaft to move the clutch plate under reaction of load on the transmission away from one of said pair of members when the shaft is moved to release the pressure of the clutch plate on said one clutch member, an end thrust bearing for said helical gear for preventing the shaft from being moved by said gear beyond a neutral position between said clutch members, and yielding means for retaining the clutch plate out of engagement with the other of said pair of clutch members.

6. A driving and stopping mechanism having, in combination, a drive shaft, high and low speed clutch members rotatable on the shaft, a central clutch plate secured to the shaft between the clutch members, manually operable means for shifting the shaft endwise to control the pressure of the clutch plate against the low speed clutch member, power actuated means for disengaging the clutch plate from the low speed clutch member and actuating it against the high speed clutch member, and a transmission for the power actuated means, comprising a helical gear on the shaft having teeth cut at an inclination to the axis of the shaft to cause the reaction of the helical gear on the shaft to move the clutch plate away from the low speed clutch member when the pressure is released by the manually actuatable means, with a load imposed on the transmission.

7. A driving and stopping mechanism having, in combination, a shouldered drive shaft, high

and low speed clutch members rotatable on the shaft, a central clutch plate secured to the shaft between the clutch members, manually operable means for shifting the shaft endwise to control the pressure of the clutch plate against the low speed clutch member, power actuated means for disengaging the clutch plate from the low speed clutch member and actuating it against the high speed clutch member, a transmission on the shaft having teeth cut at an inclination to the axis of the shaft to cause the reaction of the transmission under load to move the helical gear against the shoulder on the drive shaft and the clutch plate away from the low speed clutch member when the pressure is released by the manually operable means, and a thrust bearing for preventing the reaction of the transmission from moving the clutch plate against the high speed clutch member.

8. A driving and stopping mechanism having, in combination, a main shaft, a high speed clutch for driving the shaft, a low speed braking clutch member slidable along the shaft, a low speed driver on the shaft, and means for disengaging the high speed clutch and for engaging the braking clutch member with the low speed driver, comprising a radially cut timing cam connected to the braking clutch member, a follower engaging the cam at one side of the shaft, means for causing the braking clutch member to engage its driver, and thrust means engaging a radial surface on the braking clutch member at the side of the shaft opposite from the cam follower to equalize the pressure between the braking clutch member and its driver at opposite sides of the shaft.

9. A driving and stopping mechanism having, in combination, a main shaft, a high speed clutch for driving the shaft, a low speed braking clutch member slidable along the shaft, a low speed driver on the shaft, and means for disengaging the high speed clutch and for engaging the braking clutch member with the low speed driver, comprising a radially cut timing cam connected to the braking clutch member, a follower engaging the cam at one side of the shaft, a yielding slide, means for coupling the follower to the slide to cause the braking clutch member to engage its driver, and thrust means engaging a radial surface on the braking clutch member at the side of the shaft opposite from the cam follower to equalize the pressure between the braking clutch member and its driver at opposite sides of the shaft.

10. A driving and stopping mechanism having, in combination, a main shaft, a high speed clutch for driving the shaft, a low speed braking clutch member slidable along the shaft, a low speed driver on the shaft, and means for disengaging the high speed clutch and for engaging the braking clutch member with the low speed driver, comprising a radially cut timing cam connected to the braking clutch member, a follower engaging the cam at one side of the shaft, a slide, means for coupling the follower to the slide to cause the braking clutch to be driven, thrust means engaging a radial surface on the braking clutch member at the side of the shaft opposite from the follower to equalize the pressure between the braking clutch member and its driver at opposite sides of the shaft, and yielding means interposed between the slide and the thrust means.

11. A driving and stopping mechanism having, in combination, a main shaft, a high speed clutch

for driving the shaft, a low speed braking clutch member slidable along the shaft, a low speed driver on the shaft, and means for disengaging the high speed clutch and for engaging the braking clutch member with the low speed driver, comprising a radially cut timing cam connected to the braking clutch member, a follower engaging the cam at one side of the shaft, a yielding slide, means for coupling the follower to the slide to cause the braking clutch member to engage its driver, a thrust lever, means carried by the thrust lever engaging a radial surface on the braking clutch member at the side of the shaft opposite from the follower to equalize the pressure between the braking clutch member and its driver at opposite sides of the shaft, and a spring interposed between the slide and the thrust lever.

12. A driving and stopping mechanism having, in combination, a main shaft, a high speed clutch for driving the shaft, a braking clutch member slidable along the shaft, a cooperating clutch member on the shaft, and means for disengaging the high speed clutch and for engaging the braking clutch member with its cooperating member, comprising a radially cut timing cam connected to the braking clutch member, a lever vibrated by the timing cam, a lock bolt for causing the lever to be restrained against movement by the timing cam when the high speed clutch is disengaged, a lock bolt carrier mounted to move at right angles to the lock bolt, and thrust means connected to the lock bolt carrier for engaging a radial surface on the braking clutch member at the side of the shaft opposite from the follower to equalize the pressure between the braking clutch member and its cooperating member at opposite sides of the shaft when the lock bolt engages the vibrating lever.

13. A driving and stopping mechanism having, in combination, a main shaft, a high speed clutch for driving the shaft, a braking clutch member slidable along the shaft, a cooperating clutch member on the shaft, and means for disengaging the high speed clutch and for engaging the braking clutch member with its cooperating member, comprising a radially cut timing cam connected to the braking clutch member, a lever vibrated by the timing cam, a lock bolt for causing the lever to be restrained against movement by the timing cam when the high speed clutch is disengaged, a lock bolt carrier mounted to move at right angles to the lock bolt, a thrust lever yielding connected to the lock bolt carrier, and a roll on the thrust lever engaging a radial surface on the braking clutch member at the side of the shaft opposite from the vibrating lever to equalize the pressure between the braking clutch member and its cooperating member at opposite sides of the shaft when the lock bolt engages the vibrating lever.

14. A driving and stopping mechanism having, in combination, a main shaft, a high speed clutch for driving the shaft, a low speed braking clutch member slidable along the shaft, a low speed driver on the shaft, and means for disengaging the high speed clutch and for engaging the braking clutch member with the low speed driver, comprising a radially cut timing cam connected to the braking clutch member, a follower engaging the cam at one side of the shaft, a slide, means for coupling the follower to the slide to cause the braking clutch to be driven, thrust means engaging a radial surface on the braking clutch member at the side of the shaft opposite from the follower to equalize the pressure between the braking clutch member and its driver at opposite sides of the shaft.

15. A driving and stopping mechanism having, in combination, a main shaft, a high speed clutch

75 from the follower to equalize the pressure be-

tween the braking clutch member and its driver at opposite sides of the shaft, and yielding means interposed between the slide and the thrust means proportioned to cause the force applied to the thrust means to balance the force applied to the follower.

15. A driving and stopping mechanism having, in combination, a main shaft, a high speed clutch for driving the shaft, a braking clutch member slideable along the shaft, a cooperating clutch member on the shaft, and means for disengaging the high speed clutch and for engaging the braking clutch member with its cooperating member, comprising a radially cut timing cam connected to the braking clutch member, a lever vibrated by the timing cam, a lock bolt for causing the

lever to be restrained against movement by the timing cam when the high speed clutch is disengaged, a lock bolt carrier mounted to move at right angles to the lock bolt, a spring acting on the lock bolt carrier to maintain the carrier yieldingly in position, thrust means connected to the carrier for engaging a radial surface of the braking clutch member at the side of the shaft opposite from the follower and a spring connecting the thrust means and carrier proportioned to apply together with the carrier spring a pressure which is inversely proportional to the ratio of the distance between the cam follower and the center of the shaft to the distance between the thrust means and the center of the shaft.

CLYDE L. KNOTT.
